HOUSE TRAILER

Roy Goettsche, Saginaw, Mich.

Application February 16, 1953, Serial No. 23,644

Term of patent 14 years

(CL. D14—3)

To all whom it may concern:

Be it known that I, Roy Goettsche, a citizen of the United States, residing in Saginaw, county of Saginaw, State of Michigan, have invented a new, original, and ornamental Design for a House Trailer, of which the following is a specification, reference being had to the accompanying drawing forming a part thereof.

Figure 1 is a perspective view of a house trailer, shown on a reduced scale, embodying my new design;

Figure 2 is a front elevational view of the said trailer; and

Figure 3 is a right side elevational view of only the dominant portion of said house trailer.

The dominant feature of my design resides in the full line portions.

I claim:

The ornamental design for a house trailer, substantially as shown and described.

ROY GOETTSCHE.
